CLAIM

The ornamental design for light bezel for a vehicle, as shown and described in FIGS. 1-10.

DESCRIPTION

The file of this patent contains at least one drawing executed in color. Copies of this patent with color drawing(s) will be provided by the Patent and Trademark Office upon request and payment of the necessary fee. The color shown on the claimed design forms no part thereof.

FIG. 1 is a front view of a component in a lighting device; FIG. 2 is a rear view of the lighting device component shown in FIG. 1;

FIG. 3 is a right side view of the lighting device component shown in FIG. 1;

FIG. 4 is a perspective view of the lighting device component shown in FIG. 1;

FIG. 5 is another view of the lighting device component shown in FIG. 1;

FIG. 6 is a view of the opposite side of the lighting device component shown in FIG. 5;

FIG. 7 is a perspective view of the lighting device component shown in FIG. 1;

FIG. 8 is a rear view of the lighting device component shown in FIG. 1;

FIG. 9 is another rear view of the lighting device component shown in FIG. 1; and,

FIG. 10 is a still another view of the lighting device component shown in FIG. 1.
